UNITED STATES PATENT OFFICE.

RUFUS N. PRATT, OF HARTFORD, CONNECTICUT, ASSIGNOR TO THE PRATT & CADY COMPANY, OF SAME PLACE.

STEAM-VALVE.

SPECIFICATION forming part of Letters Patent No. 292,353, dated January 22, 1884.

Application filed November 20, 1882. (No model.)

To all whom it may concern:

Be it known that I, RUFUS N. PRATT, of Hartford, in the county of Hartford and State of Connecticut, have invented certain new and useful Improvements in Steam-Valves, of which the following is a description, reference being had to the accompanying drawings, where—

Figure 1 is a side view of my improved valve, parts being cut away and others in section. Fig. 2 is a side view of same, with part cut away to show interior of body. Fig. 3 is a detail rear view of the carrier-block. Fig. 4 is a detail front view of same. Fig. 5 is a view in vertical longitudinal section on a plane at right angles to the plane of view of Fig. 1. Fig. 6 is a detail edge view of the flap, showing the side mortises. Fig. 7 is a detail top view of the flap.

My improvement relates to the class of steam-valves in which the flap or valve is pivoted within the body of the valve and operated by a spindle arranged at an angle to the valve-seat.

It consists of the devices used to close the steamway securely, and to make the valve readily operative under the back-pressure upon the hinged flap.

In the accompanying drawings, the letter *a* denotes the body of a valve as a whole; *b*, a vertical branch, (with usual stuffing-box,) in which the spindle *c* and carrier-block *d* are arranged to operate; *e*, an angular branch opposite and giving access to the flap *f* when the valve is inserted in a line of pipe. The flap *f* is pivoted to the body *a*, and bears the rotary disk *g*, that covers the steamway *h* in the inclined valve-seat *i*. The stem *g'* of the rotary disk *g* has a slotted head, by which the disk may be ground to its seat by means of a screw-driver inserted through the branch *e*.

The flanged foot of the spindle *c* fits in the laterally-open socket in the top of the carrier-block, and by this means the spindle can rotate freely in moving the block to open and close the valve. The carrier-block *d* is cut away centrally below the socket, (see Figs. 1, 3, and 4,) for the free passage of the stem *g'* of the valve, forming what may be called the wings *k* of the block. The front and rear

edges of these wings are parallel with each other and with the axis of the spindle, the front edges, *d'*, being in sliding contact with the guides *a²*, and the rear edges, *k'*, bearing against the guides *a³*, formed on the inner side of the valve-body. These guides are parallel with each other, and may be called vertical, as shown in the drawings.

Upon the inner sides of the wings *k* are lugs *k²*, that take into mortises *f'* on each side of the flap *j*, and by means of these the flap is raised and lowered as the carrier-block is reciprocated by the spindle. The parts of the wings of the block forming the bearings *k'* are thrown out laterally slightly beyond the sides, and the part *d²* of each wing, just inside the vertical bearing-faces, is inclined to the plane of the front bearings, *d'*, forming with them a wedge, the rear or under side of which bears upon the back of the flap on either side of the stem. This construction of the back of the block *d* is shown in detail in Fig. 3, and also in Fig. 2, where a part of the nearest wing is cut away to show the surface *d²* in contact with the back of the flap.

Devices similar to the wedge have been used in sliding valves; but under back-pressure the block with the wedge feature alone is apt to spring the spindle and jam. The same defect would exist in my form of valve, in which a pivoted flap is used; but I remedy it by means of the wing-bearings and guides in the body.

I claim as my invention—

1. In a steam-valve, in combination, body *a*, having branches *b* and *e* and inclined valve-seat *i*, hinged flap *f*, bearing a rotary disk, *g*, and a carrier-block, *d*, provided with front and rear bearings, and reciprocated between guides by means of spindle *c*, all substantially as described.

2. In a steam-valve, a carrier-block having bearing-surfaces adapted to work between guides within the valve-body, and also an inclined bearing, forming with the front bearing a wedge between the valve-body and the hinged flap, all substantially as described.

RUFUS N. PRATT.
